UNITED STATES PATENT OFFICE

2,511,919

INSERTABLE TYPEWRITER SUPPORT FOR
DESKS

James R. Jones and Floyd H. Bloomstran, Jamestown, N. Y., assignors to Art Metal Construction Company, Jamestown, N. Y.

Application November 13, 1947, Serial No. 785,600

2 Claims. (Cl. 311—17)

1

This invention relates to improvements in desks and particularly to an improved platform unit or insert for installation in desks of usual or ordinary type for supporting a typewriter or analogous machine in position for operation, thereby adapting a desk, such as a regular office desk, for use as a typist's or secretarial desk.

A primary object of the invention is to provide a platform or insert unit which can be instantly and easily installed in an ordinary desk and provide desirable means for supporting a typewriter or the like in position for operation.

Other objects of the invention are to provide a novel typewriter or the like supporting unit or insert comprising a drawer and an attached typewriter platform which can be instantly inserted in a drawer opening or space of a desk in place of the regular desk drawer and firmly retained with the platform projecting forwardly from the desk and forming a firm, stable support for the typewriter or the like in its operative position; to provide the platform unit or insert with a part arranged to engage or interlock with a part of the desk when inserting the unit in place in the drawer opening or space and securely retain the unit in operative position in the desk so as to ensure a firm, steady support for the machine; and to provide a desk typewriter or the like platform unit or insert of novel construction which will afford a strong, rigid support for the machine.

Further objects and advantages of the invention will appear from the following specification of the preferred embodiment of the invention shown in the accompanying drawings, and the novel features of the invention are set forth in the appended drawings.

In said drawings:

Fig. 1 is a fragmentary, perspective view of a desk equipped with a typewriter platform unit or insert embodying the invention.

Fig. 2 is a perspective view, enlarged, of the typewriter platform unit or insert apart from the desk.

Fig. 3 is a broken, approximately full scale, transverse vertical section of the platform on line 3—3, Fig. 2.

Fig. 4 is a broken, sectional plan view of the desk and platform unit, on an enlarged scale, on line 4—4, Fig. 1.

Fig. 5 is a vertical, sectional elevation thereof on line 5—5, Fig. 4.

10 represents a drawer pedestal of a flat top office desk of regular or ordinary type which may have either a single pedestal, or right and left hand pedestals at opposite ends of the desk, as usual in office desks. The pedestal, or each of the pedestals in a two pedestal desk, may, as usual, house a plurality of drawers, two of the regular desk drawers being shown at 11, Fig. 1. As il-

2

lustrated in Fig. 1, the uppermost regular drawer of the desk has been removed and the typewriter platform unit, shown in Fig. 2, has been installed in the drawer space or opening in place of the regular drawer, which has been removed.

This invention is not concerned with the construction of the desk itself, which may be of usual or any suitable construction providing space or compartments for drawers in each pedestal, and drawer guides or rails (not shown), for slidably supporting the drawers for in and out movement. However, the desk, as shown in Fig. 5, is provided at the upper portion of the pedestal below the desk top with the usual inwardly and outwardly movable sliding shelf 12 and the usual fixed or stationary cross rail 13 at the front of the desk immediately below said sliding shelf and dividing the shelf space or compartment from the drawer space for the top desk drawer or drawer next below the sliding shelf.

The platform unit or insert comprises a drawer 15 and a platform 16 fixed to the drawer and projecting forwardly from the front end thereof. This drawer may be of the same form and construction as the regular desk drawer, which has been removed to permit the installation of the platform unit, or the unit drawer 15 may be of other suitable form and construction adapting it to be inserted into the desk in place of the regular drawer, and to be slidably supported in the desk by the supporting guides or rails for the regular drawer. The unit drawer shown may have the usual upright front or front wall 17 and opposite side walls 18 provided with rails 19 adapted to cooperate with the guides or rails in the desk pedestal for slidably supporting the unit drawer and always firmly maintaining it horizontal.

The platform 16 is preferably of the construction illustrated, comprising a horizontal sheet metal top plate 20 having relatively deep, depending stiffening and strengthening flanges 21 at its opposite sides and front end, the bottom edge portions of which flanges may be reversely bent upon themselves to further stiffen the flanges. A marginal, vertical metal strip 22 surrounds the front end and opposite sides of the platform, being rigidly attached as by spot welding, to the depending flanges 21 and projecting above the upper face of the top plate 20 to provide a raised curb at the sides and front end of the platform to prevent accidental displacement of the machine from the platform and, as shown, the platform may be provided with a linoleum or the like cushioning cover sheet 23 cemented or otherwise secured on the top plate.

The platform is rigidly attached to the drawer 15 by a pair of longitudinal supporting bars 24 which are rigidly attached, as by spot welding, to the underside of the platform top plate 20, and preferably extend from approximately the front

end of the platform rearwardly beyond the rear end of the platform through suitable openings 25 in the front 17 of the drawer 15, with the supporting bars bearing against the inner faces of the side walls of the drawer, to which they are rigidly attached, as by screw bolts 26. These supporting bars 24 are preferably of the cross sectional channel or flanged shape shown in Fig. 3, having their upper flanges welded to the platform top plate 20 and having the inner margins of their lower flanges turned upwardly to add greater stiffness and rigidity to the bars. The platform is preferably of greater horizontal width than the drawer to which it is attached to enable a typewriter to be placed in a sidewise facing position thereon, and since the supporting bars 24 are spaced apart a distance corresponding with the cross width of the drawer, they are located substantial distances inwardly from the side edges of the platform and cooperate with the side and end flanges 21 and marginal curb strip 22 of the platform to give great strength, stiffness and rigidity to the platform.

The platform is provided at its inner or rear end with a holding hook or member 27 arranged to engage or interlock with the desk cross rail 13 above the platform unit drawer 15 for holding the platform unit in its intended place in the desk and resisting or preventing unintentional forward movement or displacement of the unit. Preferably, as shown, the rear end of the platform top plate 20 is bent or flanged upwardly at 28 and then rearwardly to form the holding hook or member 27 which is adapted to extend into the desk between the top of the fixed cross rail 13 and the sliding desk shelf 12. At its rear extremity this holding member is formed with a depressed offset or transverse rib 29 adapted to engage the rear edge of the cross rail 13 and thereby resist or prevent forward movement or displacement of the platform unit, which may be held from movement inwardly beyond its intended operative position, as by the engagement of parts of the unit drawer with stop parts on the desk, as is usual in desk drawer constructions.

To install the platform unit, it is only necessary to remove a regular drawer (which may be the top drawer of either a right or left hand desk pedestal) from the desk and insert the unit drawer 15 in its place and shove the unit inwardly until the holding member or hook 27 enters the space between the cross rail 13 and the sliding shelf 12, and the inward movement of the unit is arrested by a suitable stop on the desk. There is sufficient space between the bottom of the desk shelf 12 and the top of the cross rail 13 to permit the entrance of the holding member, but preferably the parts are so proportioned and positioned that the offset rear end of the holding member is deflected upwardly slightly by engagement of its bevelled underface with the cross rail 13, and when the unit has been shoved inwardly to its intended operative position in the desk, the offset end of the holding member will spring downwardly, due to the inherent resilience of the holding member, and engage the rear edge of the cross rail so as to securely hold the platform unit in its operative position in the desk against unintentional or accidental forward movement or displacement. However, when it is desired to remove the unit from the desk, it is simply necessary to exert sufficient forward pull on the unit to spring the hooked or offset end of the holding member out of holding engagement with the rear edge of the cross rail 13. The under face of the

70 offset may be forwardly bevelled, as shown, to permit such forcible withdrawal of the unit.

In case there is not sufficient space between the sliding shelf 12 and the rail 13 to permit the offset end 29 to pass through this space, the shelf 5 may be removed by completely drawing the same out of the desk, whereupon the unit drawer 15 may be inserted in place of the top drawer of the desk pedestal. The hook member 27 may then 10 be slid over the cross rail 13 so that the offset end 29 is at the rear edge of the cross rail. Upon replacing the sliding shelf 12, the offset end will be held in place, by the shelf and the cross rail, thus securely locking the platform unit in place. 15 When it is desired to remove the platform unit, this can readily be done by first removing the sliding shelf 12, whereupon the platform unit may be drawn forwardly by springing the offset end 29 upwardly over the cross rail 13.

20 We claim:

1. A unit for supporting a typewriter or the like in operative position at the front of a desk having a fixed cross rail at the front thereof above a drawer space, comprising a drawer and a platform carried by and projecting forwardly from said drawer, said drawer being insertable into a drawer space of the desk, and bars for fixing said platform rigidly to said drawer, said bars being rigidly attached to the underside of said platform in locations spaced inwardly from the side edges of the platform and extending rearwardly from approximately the front end of the platform beyond the rear end of the platform through openings in the front of said drawer and being fixed rigidly to the side walls of the drawer.

35 2. A unit for supporting a typewriter or the like in operative position at the front of a desk having a fixed cross rail at the front thereof above a drawer space, comprising a drawer and a platform carried by and projecting forwardly from

40 said drawer, said drawer being insertable into a drawer space of the desk, said platform comprising a top plate having depending stiffening flanges along its side edges and front end, and a vertical marginal strip extending around the sides and outer end of said platform plate and attached to said depending plate flanges and forming marginal flanges projecting above the top face of the platform, and flanged bars for fixing said platform rigidly to said drawer, said bars being welded to the underside of said top plate in locations spaced inwardly from the sides of the platform and extending rearwardly from approximately the front end of the platform beyond the rear end of the platform through openings in the front of said drawer, and being fixed rigidly to the side walls of the drawer.
